UNITED STATES PATENT OFFICE.

WALTER S. DANIELS, OF NEW YORK, N. Y.

FLOWER-HOLDER.

1,081,027.

Specification of Letters Patent.

Patented Dec. 9, 1913.

Application filed July 1, 1912. Serial No. 706,945.

To all whom it may concern:

Be it known that I, WALTER S. DANIELS, a citizen of the United States, and a resident of the city of New York, borough of Manhattan, in the county and State of New York, have invented a new and Improved Flower-Holder, of which the following is a full, clear, and exact description.

This invention relates to flower holders for use in arranging and positioning flowers or the like in vases, bowls or other receptacles intended for their reception, and has reference more particularly to a device of this class which comprises a plurality of rods adapted to have the stems of flowers disposed among them to hold the flowers in place.

The object of the invention is to provide a simple and efficient flower holder which can be inexpensively produced, which can be fashioned from different materials and constructed in different sizes and proportions, by means of which flowers can be disposed in artistic and ornamental arrangement in vases, bowls or the like, and which facilitates the arrangement of the flowers in flat receptacles or receptacles of considerable size.

The invention consists in the construction and combination of parts to be more fully described hereinafter and particularly set forth in the claim.

Reference is to be had to the accompanying drawings forming a part of this specification, in which similar characters of reference indicate corresponding parts in all the views, and in which—

Figure 1 is a perspective view showing an embodiment of my invention, certain parts being shown in different positions in dotted outline; Fig. 2 is a perspective view showing a bowl with flowers arranged therein and held in position by means of my device; and Fig. 3 is a fragmentary, vertical section showing a detail of modified construction.

Before proceeding to a more detailed explanation of my invention, it should be clearly understood that while the device is designed particularly to assist in the positioning and arrangement of flowers and the like used for decorative purposes on tables at meal times and on other similar occasions, the holder can also be utilized for other purposes wherein it is necessary or desirable to arrange and hold objects such as cut flowers, in position.

I prefer to fashion the device from metal which will give sufficient weight so that it will stay submerged in a bowl or other receptacle filled with water. Furthermore, the rods are preferably fashioned from metal which permits them to be readily bent into different positions to facilitate the use of the device.

Certain of the details of construction shown for example herewith, form no part of the invention and can be varied in accordance with individual preference and special conditions, without deviating from the underlying spirit of the invention.

Referring more particularly to the drawings, I have shown for example a flower holder having a base 10 which is fashioned from lead or the like and is in the form of a disk of substantial thickness. I provide a plurality of rods 11, the lower ends of which are embedded in the base 10. The rods extend upwardly and are normally approximately parallel. They are fashioned from iron wire or other material which permits them to be bent into different positions, as is indicated in dotted outline. The rods may be of any suitable lengths adapted for the purpose, and may be of any desired number, though I have shown for example twenty of them.

In fashioning the device, lead is run into a suitable mold to provide the base, and the ends of the rods are then introduced into the metal while it is still plastic. As soon as it has hardened the rods will be securely held in position.

In the modified form of the device shown in Fig. 3 I provide a base 12 having a plurality of threaded openings 13 in which are received the correspondingly threaded lower ends 14 of the rods 15. With this form of the device the number of the rods may be varied.

When in use the holder is positioned in a bowl or other receptacle 16, preferably at the center thereof. The flowers 17 are then arranged in the bowl with their stems 18 inserted or even entwined among the rods 11. The holder it will be understood, permits the flowers at the center of the bowl, where they normally have no support, to be positioned and held in a bank or rounded mass. The flowers at the edge of the bowl can of course be supported in the usual manner, upon the rim.

It will be understood that where a flat

vessel or one of considerable proportions is employed it is difficult to form a bank or mass of the flowers owing to the fact that the same have no support at the center of the receptacle. This deficiency my device is designed to overcome, although it can be used for other purposes and with different types of vases or flower receptacles.

Having thus described my invention, I claim as new, and desire to secure by Letters Patent:—

A flower holder comprising a flat, non-floating base adapted to stand upon the bottom of the vessel, and a plurality of rods 15 having their lower ends attached to said

base, and the upper ends projecting above the upper surface of said base, and having predetermined, normal positions relative to one another, said rods being evenly distributed within the periphery of the upper 20 surface of said base, and being formed of pliable material for the purpose specified.

In witness whereof I have signed my name to this specification in the presence of two subscribing witnesses.

WALTER S. DANIELS.
